UNITED STATES PATENT OFFICE.

ROBERT KOENIG, OF BROOKLYN, NEW YORK, ASSIGNOR TO PHENIX TUBE COMPANY,
OF BROOKLYN, NEW YORK, A CORPORATION OF NEW JERSEY.

TUBE-DRAWING MACHINE.

1,019,805.

Specification of Letters Patent. Patented Mar. 12, 1912.

Application filed May 18, 1911. Serial No. 627,950.

To all whom it may concern:

Be it known that I, ROBERT KOENIG, a citizen of the United States, and resident of Brooklyn, in the county of Kings and State of New York, have invented new and useful 5 Improvements in Tube-Drawing Machines, of which the following is a specification.

My invention relates to the manufacture of sheathed tubes, which are composed of an 10 inner seamed tube of steel or iron, and an outer seamed covering of metal such as brass, the inner tube contributing strength and the covering or sheathing giving the desired finish. Such tubes are made by 15 forming bands of metal into split or seamed tubular shape, and are usually brazed at the seam. The heretofore used method of making such sheathed tubes is that described in Skogse's United States Patent No. 617,363, 20 dated January 10, 1899, and large quantities of sheathed tubing have been produced by this method, though it presents sundry defects which it is the object of my present invention to remedy. Chief among these 25 defects, incidental to the Skogse method, are departure from true cylindrical form in the finished tube, and waste, due to damage of the thin relatively delicate brass sheathing by roughness and irregularities of the inner 30 steel core-tube. The rolling and shaping of the inner steel tube, by the Skogse method involves the application of rolling pressure from the unyielding rolls through the thin brass strip, and the inevitable occasional 35 roughnesses and irregularities in the steel core bruise and tear the thin brass.

My invention consists in a drawing machine for sheathing tubes, and is exemplified by the machine illustrated in accompanying 40 drawings, in which—

Figure 1 is a top plan view of the sheath forming and tube drawing devices, Fig. 2 is a view, partly in side elevation and part section of the said devices, Fig. 3 is an end 45 elevation (viewed from the left in Fig. 1) of portions of the machine, Fig. 4 is a cross section of portions of the machine, taken at the line 4—4 of Fig. 1, viewed in the direction shown by the arrow, Fig. 5 is a cross section taken at line 5—5, Fig. 1, showing part of the edge turning die and the two tube members, Fig. 6 is a cross section taken at the line 6—6, Fig. 1, and Fig. 50 5 is a plan view, showing the gradual de-

velopment of the materials into a completed 55 sheathed tube, ready for brazing.

The core tube T is first prepared by rolling from a strip in a machine such as is shown in the said Skogse patent, or by other means if practicable or desired, so that when 60 it is introduced into the sheathing machine it has had all roughnesses and protuberances rolled smooth by the hardened surfaces of the rolls in the forming machine, and is thus in condition to receive a thin sheath of 65 brass or other suitable sheathing metal.

The drawing machine is provided with a suitable drawing head or "dog" (not shown) such as is usual in drawing benches, and with a standard D, on which the bridge 70 C is mounted. The bending funnel E is secured in the standard D, and the tube guide F, provided with the depending web F' is secured to the bridge C. Die plates M and M' are secured to the draw-bench, 75 the die plate M having a slightly conoidal constricting die at m, and the plate M' a finishing die at m'. The edge-turning die L is mounted in the constricting die opening, and presents to the tube-members a 80 central fin L' and inclined edge-turning surfaces L².

The tube-core T, with its longitudinal open seam T' is introduced through the bending funnel E, the seam T' embracing 85 the tube guide F', which guides the tube T so that the fin L' of the edge turning die will also enter the seam T'. A strip B, of brass or other suitable metal, drawn from the reel R, is introduced into the funnel E, 90 and thereby bent upwardly around the tube core T. The narrowed end of the bending funnel E, shown in Fig. 4, delivers the sheath-strip B to the edge-turning surfaces L² of the edge-turning die L; the die L 95 turns the edge of the sheath-strip inward and downward into the open seam T' of the tube core T, as shown in Fig. 5. As the tube core T and inturned sheath strip B pass farther into the constricting die at m, the 100 development of the edge-turning surfaces L' and the conoidal constricting form of the die m coöperate to draw the edges of the seam T' together, crowding the inturned folds of the sheath strip into close engagement with the fin L' and thus, by reason of the flow of metal, turning the edges of the sheath strip under the edges of the seam T', 105

as illustrated in Fig. 6. Thence the sheathed tube passes to the finishing die m' , where the seam is drawn close, and final true cylindrical form given to the sheathed tube, 5 which is then ready to be brazed. By thus using a tube - core which has been rolled smooth and then folding, edge turning and drawing a tube-sheath over it, engaging the sheath with the core at their common seam, 10 and finally drawing the sheathed tube in a finishing mandrel, a truly cylindrical finished product results, and waste due to injury of the sheath is avoided.

What I claim and desire to secure by Letters Patent is:

1. In a drawing machine for sheathing seamed tubes, the combination of a tube guide to extend through the seam of a tube to be sheathed, an edge-turning die to infold

the edges of a tube sheath into the seam of a 20 tube, a guide fin alined with the tube guide and midway of the edge turning die surfaces, and a constricting die.

2. In a drawing machine for sheathing seamed tubes, the combination of a bending 25 funnel, a tube guide to extend through the seam of a tube to be sheathed, an edge-turning die to infold the edges of a tube sheath into the seam of a tube, a guide fin alined with the tube guide and midway of 30 the edge turning die surfaces, and a constricting die.

Signed by me at Brooklyn, New York, this 15th day of May 1911.

ROBERT KOENIG.
